UNITED STATES PATENT OFFICE.

CHARLES J. BUCHHEIT AND EDWARD C. LOVERIDGE, OF BUFFALO,
NEW YORK.

DESIGN FOR A BADGE.

SPECIFICATION forming part of Design No. 29,957, dated January 10, 1899.

Application filed December 19, 1898. Serial No. 699,774. Term of patent 3½ years.

To all whom it may concern:

Be it known that we, CHARLES J. BUCHHEIT and EDWARD C. LOVERIDGE, residing at Buffalo, in the county of Erie and State of New York, have invented and produced a new and original Design for Badges, of which the following is a specification, reference being had to the accompanying drawing, forming part thereof.

10 The accompanying drawing is a front elevation of our new design for badges.

As shown in the drawing, the leading feature of our design consists of a miniature pan A, having a handle B and the figure or head 15 of a bison or buffalo in relief in the depressed portion or bottom of the pan A. The pan and

handle may, it is manifest, be engraved, chased, or otherwise ornamented, as desired.

It is apparent that this design is also applicable to watch-chains, scarf-pins, lapel- 20 buttons, and other similar articles.

Having described our invention, what we claim as new, and desire to secure by Letters Patent, is—

25 The design for a badge substantially as herein shown and described.

CHARLES J. BUCHHEIT.
EDWARD C. LOVERIDGE.

Witnesses:

H. E. CURTIS,
GEO. E. BINGERT.
